IMPROVEMENT IN SAW MILLS.

JAMES A. HOLFORD OF GUIONSVILLE, INDIANA.

Letters Patent No. 60,374, dated December 11, 1866.

The Schedule referred to in these Letters Patent and making part of the same.

TO ALL WHOM IT MAY CONCERN:

Be it known that I, JAMES A. HOLFORD, of Guionsville, in the county of Dearborn, and State of Indiana, have invented a new and improved Circular Saw Mill; and I do hereby declare that the following is a full, clear, and exact description thereof, which will enable others skilled in the art to make and use the same, reference being had to the accompanying drawings, forming part of this specification, in which—

Figure 1 represents a plan or top view of my improved saw mill; and

Figure 2, a front elevation of the same.

Figure 3 is a vertical longitudinal section of the carriage, taken on the line $z z$, fig. 1.

Figure 4 is a vertical cross section of the same, taken on the line $y y$, fig. 1.

Figure 5 is a detailed sectional view, taken on the line $y y$, fig. 3.

Similar letters of reference indicate like parts.

This invention relates to certain improvements in circular saw mills by which the whole machine will work automatically in all its parts, and by which the log when placed upon the carriage is cut into boards of the requisite thickness, without requiring the least attention from any men.

The invention consists, first, in a combination of certain parts of the machine by which an automatic setting motion is attained, that is, the log, after a board has been cut off, is shoved forward the thickness of the board by the machine itself. This setting apparatus can be so regulated that any desired thickness of board may be cut and set. Second, my invention consists in an automatic feed motion, by which the motion of the carriage is reversed as soon as the log is cut, the carriage then returns to its starting point, when the log is adjusted by the aforesaid setting motion, and the machine is then again reversed so as to propel the log against the saw.

The driving pulley A, which is supported by the standards a , standing on the floor B of the machine, drives by means of the belt b , the shaft C, to which the saw D is attached. Another belt, c , drives the conical pulleys E and F, which are connected by the belt d . The belt d can be moved up or down the conical pulleys by means of the forked lever e , attached to a bar, f , below the floor B, and operated by a lever, g , as seen, whereby the motion of the pulley F and its shaft, f' , may be regulated. A pulley, f'' , on the shaft f' drives, by means of the belts h and i , the latter of which is crossed respectively, the loose pulleys h' and i' on the shaft K. A sleeve, h^2 , travelling on a squared or grooved part of the shaft K, gives the desired motion to the pinion K', when said sleeve is brought in contact with one of the pulleys h' or i' . The pinion K' drives, by means of the cog-wheel I, the shaft G on the outer end of which a pinion g' is attached, which works into a rack-bar, g^2 , attached to the under side of the carriage H. Two stop-levers, h^2 and h^3 , at the ends of the carriage, when coming in contact with the reversing lever h^4 , reverse the motion of the carriage. The reversing lever is pivoted on a pin l' , and operates by means of a connecting rod, l'' , the sleeve h'' , whereby the motion of the shaft G is reversed. The reversing lever h^4 is held in place by a spring, m . The motion of the carriage may be stopped altogether by throwing the pinion g' out of gear, which is done by means of a lever, n , which, being connected to the outer bearings of the shaft G by a connecting rod n' , throws this bearing, and with it the outer end of the shaft, down, when operated upon for that purpose. The head-blocks I and K are metal bars, provided with teeth at their under side, so that the pinions o and p on the shaft L may operate them. The shaft L, which passes longitudinally through the carriage, is provided at its end with a ratchet-wheel, r , operated upon by pawls, r' , pivoted to the lever r'' . The bars I and K slide in and are guided by their respective supports, i'' and K'' . When the carriage returns to the starting place, the lever r'' is elevated by an incline, S, and the pawls r' operate the ratchet-wheel r , shaft L, pinions o and p , and consequently also the head-blocks I and K. An adjustable rest for the lever r'' is formed by two guide-plates t , through which a pin is passed at the desired height, upon which the lever falls when the carriage is moved forward again; the height of the pin t , will, therefore, designate the thickness of the boards to be cut, which is easily understood. The shaft L is square for the purpose of always operating the pinion o , which is held by the head-block support i'' , the latter sliding longitudinally on the carriage, whereby a longer or shorter log may be placed upon the saw.

Having thus described my invention, I claim as new, and desire to secure by Letters Patent—

1. The automatic log setting device, consisting of the head-blocks I and K, pinions o and p , shaft L, ratchet-wheel r , pawls r' , lever r'' , adjustable rest t , and incline S, all constructed substantially as and for the purpose herein shown and described.

2. I claim the automatic feeding device, consisting of the carriage H, reversing lever h^4 , spring m , and stop-levers h^2 and h^3 , constructed substantially in the manner and for the purpose herein shown and described.

JAMES A. HOLFORD.
